UNITED STATES PATENT OFFICE.

JOHN SCHERNER, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

WRAPPING MACHINE.

Application filed August 4, 1922. Serial No. 579,737.

To all whom it may concern:

Be it known that I, JOHN SCHERNER, a citizen of the United States, and resident of Milwaukee, in the county of Milwaukee and State of Wisconsin, have invented new and useful Improvements in Wrapping Machines, of which the following is a description, reference being had to the accompanying drawings, which are a part of this specification.

This invention relates to wrapping machines, and more particularly to machines for wrapping rubber tires, such as motor vehicle tires or casings, with a spiral wrapping or covering strip of paper or other suitable material.

The essential object of the invention is to provide a wrapping machine in which the spirally wound covering strip is supplied with adhesive to unite the adjacent edges of the turns of the strip as it is wound about the tire so that the covering will be firmly held in place and will be prevented from unwinding, even if broken in spots, the construction providing a simple and positive feed of the adhesive to the wrapping material.

The invention further consists in the several features hereinafter set forth and more particularly defined by claims at the conclusion hereof.

In the drawings: Fig. 1 is a side elevation of a wrapping machine embodying the invention; Fig. 2 is a detail sectional view taken on the line 2—2 of Fig. 1; Fig. 3 is a detail plan view of parts of the machine; Fig. 4 is a detail plan view of parts of the machine; Fig. 5 is a detail elevation of parts of the machine.

In the drawings the numeral 6 designates a supporting table carrying a bracket 7 upon which rollers 8 are mounted which receive a belt 9 that runs over a drive pulley 10, the drive pulley, as shown, being driven by a friction wheel 11 on the shaft of an electric motor 12. An annular shuttle 13 is mounted between the rollers 8 and pulley 10 and is continuously rotated by running a portion of the belt 9 about the shuttle and then over the pulleys 8, as shown in the drawing and as well understood by those skilled in this art. The article to be wrapped, such as a tire casing 14, is supported upon spaced rollers 15, only one being shown, and a guide roller 16, in a well known manner, so that the tire moves through the eye or central opening of the shuttle as the shuttle revolves. As shown, the roller 15 is driven through a chain drive 17 from a shaft 18 having a gear connection 18' with the shaft 19 of the pulley 10, all of which is of well known construction.

A reel of paper or other suitable wrapping material 20 is mounted at a suitable point upon the shuttle 13 and passes over an arcuate guide table 21 carried by the shuttle and from there to a guide roller 22 and then over the tire. The length of this arcuate table is preferably equal to about half the circumference of the shuttle so that a relatively long length of wrapping material is disposed upon this table. The table forms a support for the paper while the adhesive is being applied thereto. To prevent the strip jumping off the table 21 which, however, is provided with flanged sides 23, a spring clip 24 carried by said table is adapted to yieldingly engage the paper strip just before the same passes down to the roller 22.

The means for applying the adhesive to the wrapper strip consists of a tank 25 containing adhesive into which a roller 26, mounted on a shaft 27, is partially immersed. The shaft 27 is journaled in the forked arms 28 of a bracket 29 which is pivotally mounted intermediate its ends at 29' upon the tank. The roller 26 is yieldingly held against a part of the wrapper strip by a spring 30 connected to the outer end of the arm 31 of the bracket and to the tank. The roller is prevented from interfering with the proper operation of the shuttle and the feed of material to the table by means of a stop, such as an adjustable set screw 32 on the arm 31 engageable with a fixed part 33 of the machine. The roller 26 is pivotally driven from the shaft 18 or other positively driven part of the machine in any suitable manner, as by means of a belt 34 running over a pulley 35 on the shaft 27, a pulley 36 on the shaft 18 and guide pulleys 37 and 38. The shuttle 13 and the roller 26 turn in opposite directions, as indicated by the arrows in Fig. 1. In order to prevent splash and to regulate the amount of adhesive supplied to the wrapper strip, a member 39 is pivotally mounted on a shaft 40 to which it may be locked in adjusted position by a thumb screw 41 and said

member is notched adjacent the roller so that a part 42 and parts 42' are closely spaced from the periphery and sides of the roller so that only a thin film of adhesive is carried up by the roller and deposited on the strip. By loosening the screw 41 the member 39 may swing upwardly. While the whole strip may have adhesive applied thereto, it is only necessary to apply adhesive where the spiral turns overlap each other and consequently the roller 26 is narrower than the strip of wrapping material applied to the tire.

With the above construction, as the tire or casing moves through the rotating shuttle the wrapping strip on the reel 20 is unwound therefrom and wound up as a spiral covering upon the tire, and as this covering strip S runs along the table 21 it receives adhesive from the roller 26 so that adjacent convolutions of the wrapping are suitably united together, the long table insuring a proper supply of adhesive to the entire length of paper as it comes from the roll. This construction insures a simple, direct feed of adhesive to the covering material prior to its being wound up around the tire without danger of stoppage of rotation of the feed roll. As is well understood, the shuttle has a hinged section which permits the placing of the tire in position for winding purposes.

I desire it to be understood that this invention is not to be limited to any specific form or arrangement of parts except in so far as such limitations are specified in the claims.

What I claim as my invention is:

1. In a wrapping machine, the combination with mechanism for wrapping a covering strip spirally about a tire or tire casing, the mechanism including a rotating shuttle carrying the wrapping material, of an adhesive-applying member mounted adjacent said shuttle, means distinct from said shuttle for positively driving said member, and means for guiding the material into feeding contact with said member.

2. In a wrapping machine, the combination with mechanism for wrapping a covering strip spirally about a tire or tire casing, the mechanism including a rotating shuttle carrying the wrapping material, of a table on the shuttle upon which the material moves, a positively driven adhesive-applying roller, means for yieldingly pressing said roller into contact with said material while passing on said table, and means for limiting the movement of said roller toward the shuttle.

3. In a wrapping machine, the combina-

tion with mechanism for wrapping a covering strip spirally about a tire or tire casing, the mechanism including a rotating shuttle carrying the wrapping material, of a table on the shuttle upon which the material moves, a positively driven adhesive-applying roller, means for yieldingly pressing said roller into contact with said material while passing over said table, an anti-splash member cooperating with said roller, and means for limiting the movement of said roller toward the shuttle.

4. In a wrapping machine, the combination with mechanism for wrapping a covering strip spirally about a tire or tire casing, the mechanism including a rotating shuttle carrying the wrapping material, of a table on the shuttle upon which the material moves, a tank, a tilting support, a positively driven roller mounted on said support and dipping into the adhesive in said tank, means for limiting the tilting movement of said support, and means coacting with said support to yieldingly press the roller into contact with said material while passing over said table.

5. In a wrapping machine, the combination with mechanism for wrapping a covering strip spirally about a tire or tire casing, the mechanism including a rotating shuttle carrying the wrapping material, of a table on the shuttle upon which the material moves, a tank, a tilting support, a positively driven roller mounted on said support and dipping into the adhesive in said tank, an adjustable stop on said support to limit the tilting movement thereof, a member in close proximity to the face and sides of the roller at its advancing side to prevent splash and regulate the feed of adhesive to the material, and means coacting with said support to yieldingly press the roller into contact with said material while passing over said table.

6. In a wrapping machine, the combination with mechanism for wrapping a covering strip spirally about a tire or tire casing, the mechanism including a rotating shuttle carrying the wrapping material, of a spring-pressed positively driven adhesive-applying roller mounted adjacent said shuttle, an adhesive supply tank into which said roller dips, a member in close proximity to the face and sides of the roller at its advancing side to prevent splash and regulate the feed of adhesive to the material, and means for guiding the material into feeding contact with said member.

In testimony whereof, I affix my signature.

JOHN SCHERNER.
